(57) **CLAIM**

The ornamental design for a watering can comprising a pump, knee pad, rose docking station and glove mounts, as shown and described.

DESCRIPTION

FIG. 1 is an isometric perspective view of the watering can comprising a pump, knee pad, rose docking station and glove mounts, displaying a knee pad containment chamber at the bottom of said watering can, a pump chamber located next to a main fluid containment chamber, an externally threaded rose docking station extending from said main fluid containment chamber, two glove mounting tabs and a first side mounted tool holding chamber.

FIG. 2 is a side elevation view thereof;

FIG. 3 is the opposite side elevation view thereof;

FIG. 4 is a front view thereof;

FIG. 5 is a rear view thereof;

FIG. 6 is a top plan view thereof; and,

FIG. 7 is a bottom view thereof.
